CLAIM

The ornamental design for a monitor, as shown and described.

DESCRIPTION

FIG. 1 is a top perspective view of one embodiment of a monitor showing our new design;

FIG. 2 is a bottom perspective view thereof;

FIG. 3 is a front elevational view thereof;

FIG. 4 is a left side elevational view thereof, the right side elevation being a mirror image thereof;

FIG. 5 is a rear elevational view thereof;

FIG. 6 is a top view thereof;

FIG. 7 is a bottom view thereof;

FIG. 8 is a top perspective view of a second embodiment of a monitor showing our new design;

FIG. 9 is a bottom perspective view thereof;

FIG. 10 is a front elevational view thereof;

FIG. 11 is a left side elevational view thereof, the right side elevation being a mirror image thereof;

FIG. 12 is a rear elevational view thereof;

FIG. 13 is a top view thereof;

FIG. 14 is a bottom view thereof;

FIG. 15 is a top perspective view of a third embodiment of a monitor showing our new design;

FIG. 16 is a bottom perspective view thereof;

FIG. 17 is a front elevational view thereof;

FIG. 18 is a left side elevational view thereof, the right side elevation being a mirror image thereof;

FIG. 19 is a rear elevational view thereof;

FIG. 20 is a top view thereof; and,

FIG. 21 is a bottom view thereof.

The broken lines represent portions of the monitor that form no part of the claimed design.

1 Claim, 6 Drawing Sheets
